CLAIM

I claim the ornamental design for a bottle, as shown and described.

DESCRIPTION

FIG. 1 is a perspective view of my new design for a bottle showing an open configuration;
FIG. 2 is a side view thereof showing a closed configuration;
FIG. 3 is a side view thereof showing one half of the bottle in an open configuration;
FIG. 4 is a side view thereof showing a closed configuration in environmental use;
FIG. 5 is an enlarged detailed view of the spout of FIG. 1, shown in an open configuration and for completeness of illustration;
FIG. 6 is an alternative view of the spout of FIG. 5, shown in a closed configuration and with environment;
FIG. 7 is a side view of my new design for a bottle showing one half of the bottle in an open configuration in environmental use; and,
FIG. 8 is a bottom view of my new design for the bottle. The broken lines illustrate environmental structure and form no part of the claimed design.
